UNITED STATES PATENT OFFICE.

AUGUSTUS SMITH, OF ROSELLE, NEW JERSEY, ASSIGNOR TO BERGEN POINT IRON WORKS, OF BAYONNE, NEW JERSEY, A CORPORATION OF NEW JERSEY.

ORDNANCE.

1,376,231.

Specification of Letters Patent. Patented Apr. 26, 1921.

Application filed November 14, 1916. Serial No. 131,290.

To all whom it may concern:

Be it known that I, AUGUSTUS SMITH, a citizen of the United States of America, and residing at Roselle, in the county of Union 5 and State of New Jersey, have invented a certain new and Improved Ordnance, of which the following is a specification.

My invention relates to ordnance and particularly to heavy ordnance such as is used 10 for coast defense. The objects of my invention may be briefly stated to be to provide (1) a new system of gun pointing for ordnance of this type, (2) an improved gun mounting, (3) means for turning the gun 15 in azimuth through 360° of arc, if necessary, without endangering the equilibrium of the mounting on the firing of the gun, (4) means for absorbing the recoil of the gun within a reasonable space, (5) means for 20 utilizing the force of recoil toward preparing the gun for the next shot.

In the accompanying more or less dia- grammatic drawings,

Figure 1 is a side elevation of a gun and 25 its mounting in which my invention is illustratively embodied in one form;

Fig. 2 is a plan of the same;

Fig. 3 is a plan of a detail;

Fig. 4 is a sectional side elevation of the 30 latter;

Fig. 5 is a sectional end elevation of the same;

Fig. 6 is a plan of portion of the gun car- riage track;

Fig. 7 is a diagram of a partial track lay- out;

Fig. 8 is a side elevation of a recoil check- ing device;

Figs. 9 and 10 are end and plan views of 40 the same;

Fig. 11 is a sectional side elevation of a gun elevating and lowering mechanism; and

Fig. 12 is a plan thereof.

To illustrate my invention I have shown 45 in Fig. 1 a typical coast defense rifle 20 which is on rigid trunnion bearings 21 solidly fastened to the girders 22 of a specially constructed railway carriage. It will be understood that instead of mounting the gun 50 trunnions directly on the frame of the carriage the gun could be carried in a sleeve whose trunnions were supported on the rail-

way carriage as in the case of a "Barbette" mount or "Navy" mount. In the two latter types of mount the shock of the recoil would 55 be immediately absorbed by a hydraulic cylinder or cylinders in the customary way, whereas in the simple style shown in Fig. 1 the shock of the recoil would be taken directly by the carriage. The choice between the two 60 types of mountings depends on the stresses involved and either may be adopted without departing from the invention on which I now seek Letters Patent. I have consequently shown the gun mounted in the simple old- 65 fashioned way as illustrated, for the sake of simplicity.

The railway carriage shown in Figs. 1 and 2 is provided with king pins 23 so that the master trucks 24, 25, may swivel with respect to the main carriage frame, while the bogie trucks 26, 27, 28, 29, in turn swivel under the master trucks on their king pins 30, so that the railway carriage as a whole 70 can easily negotiate any curves encountered 75 in a standard gage railway. The wheels 31, axles 32 and boxes 33 are all of Master Car Builder type, the weights being carried on springs (not shown) over the journals as in customary freight car practice. The lost 80 motion at the boxes and bolsters would be eliminated, when the gun is to be fired, by suitable jack screws, not shown on the drawing in the interest of simplicity.

The carriage is mounted on a track 34 so 85 that the rifle may be transported from place to place thereon. At predetermined points 35, which for convenience I will call sight- ing points, the track is preferably laid in a loop. While only a single sighting point 90 may be provided for the rifle, there may be several connected by the track so that the rifle may move from one to another, since thus as the enemy obtains the range of one sighting point, the gun may be speedily 95 shifted to another from which it can operate in safety until its range has also been ascer- tained. This further enables the defense to concentrate several rifles at one sighting point, if desired, bringing them successively 100 into firing position as hereafter explained.

At the sighting points the track is spe- cially laid for the required length of arc (possibly 360°) on a true circle, as shown in

Fig. 7, and, for the length of the arc within which the gun is to be fired, the rails should be laid very carefully to level grade and accurate gage. The radius to the outer and 5 inner rails should be taken so that the circumference of the circle of either the outside of the outer rail or the inside of the inner rail heads should be accurately and definitely known. For instance, it would be 10 convenient to take either of these radii, as circumstances might indicate as preferable, so that the circumference of the circle for that portion of the track on which the gun would be fired, would be 1800 feet. In this 15 case one degree of arc would be five feet and one inch would correspond to one minute of arc. Of course it is not essential that the track at the sighting point be laid in a complete circle, since it suffices to lay it merely 20 through the arc within which the gun is to be fired, as for instance at 36 (Fig. 7). For convenience of manipulation and transfer of the carriage, however, I prefer to lay the track in a complete circle, only that portion 25 from which the gun is to be fired needing the accurate laying just mentioned.

It is clear that if the direction of a tangent to the circle at any given point with respect to the base line of the range-finding survey system were known, the distance 30 of the gun carriage along the track from the point of tangency so determined would indicate the variation of the axis of the gun in azimuth either to the right or left of the 35 known tangent, so that the direction of the gun in azimuth could be accurately determined by its position on the track measured from the given known point. This feature does away with the necessity of swinging 40 the gun on a vertical axis in azimuth on the carriage, which would obviously entail very serious results were the gun to be fired at any great angle with the center line of the track, besides involving numerous difficulties 45 in the construction of the carriage itself which are avoided by the system.

In order to center the gun more accurately with respect to the track so that dependence 50 is not placed on the flanges of the wheels, which would ordinarily have the play between the flanges and the rails, and then again in the journals, that is customary in Master Car Builders' practice, I would provide on my gun carriage at least four vertical wheels 55 arranged to bear against the inside heads of the rails, as shown in Figs. 3, 4 and 5. These would preferably be placed at the cross frames 38 of the master trucks and be pivoted at 39 so as to permit their being swung up out of the way, as shown dotted in Fig. 5 when the gun is in transit from one place to another, or to be swung down as shown by the full lines in Figs. 4 and 5 when the gun is in use on

firing. It will be understood that the screws 65 40 locating and holding these vertical wheels in firing position will be marked so that they will indicate when the gun carriage is exactly and properly placed with respect to the center of the track.

It is apparent that when direct sighting of the gun on the target is possible, accurate determination of azimuth is not essential, and for such work any curved track 70 would enable the gun to be swung in azimuth, provided only that the radius of curvature was not too small and that the length of curved track was sufficient to afford the necessary angle of fire. The fundamental principle of swinging the gun in azimuth by moving it forward and backward on the track would still obtain. The determination of the exact angle of fire would in such a case depend entirely on the 75 sights and gun pointer. For such work, 80 however, the track should be laid level to obtain correct results in elevation and range, so that it would nevertheless be to this extent a specially laid piece of track.

In order to absorb the shock of the recoil 85 I provide behind several of the axles on the car a sliding shoe 41, shown in Figs. 8, 9 and 10, which is held against the wheels on the "breech" side thereof by means of the drag chains 42 shown in Fig. 10 and 90 which are pushed backward, should the gun be moved breechward, by means of the compression springs 43. Under the shock of the recoil, however, the truck wheels 31 would mount this sliding shoe, as shown by the 95 wheel in the dotted position *a*, because the compression springs 43, provided for pushing the brake shoe breechward, would not be stiff enough to move the shoe quickly enough to keep it clear of the wheels under 100 the impulse of the recoil. The wheels, therefore, having mounted the shoe, would thereafter slide bodily along the rails on the 105 shoes as shown in Fig. 8, say from position *a* to position *b*, which sliding friction would 110 absorb the recoil of the gun within a reasonable space providing the shoes were placed under a sufficient number of the wheels of the gun carriage. It will be understood that this brake shoe device will be 115 thrown across the rails behind the wheels when the gun is in action and will be disconnected by withdrawing suitable pins 44 and 45 so as to get it out of the way altogether when the gun is to be moved for any 120 distance from one location to another.

These sliding brake shoes provide a means by which the gun can be tilted down from firing position to loading position during the interval of the recoil, utilizing the 125 energy of the recoil for power as follows:

Let us suppose that brake shoes are provided behind the wheels of trucks 26, 28 and

29 in Fig. 1, but that no brake shoes are provided behind the wheels of truck 27. Then, on recoil, the wheels of trucks 26, 28 and 29 will slide on the shoes after mounting same, as shown in Fig. 8, without revolving, while the wheels of truck 27 resting on the rails of the track will revolve as the gun carriage moves backward on the recoil of the gun.

10 This fact may be taken advantage of in a number of ways to provide power for swinging the gun from the firing position to the horizontal position in which it should be loaded. A suitable means for accomplishing this end is illustrated in Figs. 11 and 12. The wheels of truck 27 are coupled together by chain 46 running over sprockets 47, so that both drive gear 48 meshing with pinion 49 on shaft 50. The worm 51 on the 20 latter meshes with worm wheel 52 on spindle 53, and the bevel gear 54 at one end of the latter drives the double bevel wheel 55 on king pin 30, with which in turn meshes bevel gear 56 on shaft 57 carried by truck 25. Similarly the wheels of truck 26 are geared through its king pin so that when they revolve they will turn shaft 58. Now the gearing is so arranged between the truck 30 wheels and shafts 57 and 58 that if both trucks move in the same direction, either forward or backward, and the wheels thereof turn, shafts 57 and 58 will revolve in opposite directions.

On the ends of these shafts are mounted 35 the bevel gears 59 and 60 of a differential gear box such as is employed on the rear axle of an automobile, so that if shafts 57 and 58 revolve in opposite directions, no motion would be imparted to the gear 61 mounted 40 on the outside of the differential gear box; but if shaft 58 stood still while shaft 57 revolved then the gear box and the gear wheel 61 mounted on it would revolve at half of the speed of shaft 57, causing the train 45 of gears 62, 63 shown in Figs. 11 and 12, actuated by gear 61 and passing through the king pin of the master truck, to revolve. This condition would exist should the wheels 50 of truck 27 be free to revolve under the recoil of the gun, causing shaft 57 to turn while the wheels of truck 26 sliding on the shoes, did not turn, causing shaft 58 to stand. When, however, the gun carriage is moved slowly backward and forward so that 55 the sliding shoes shown in Figs. 8, 9 and 10 behind the truck wheels of bogie trucks 26, 28 and 29 could slide and keep clear of the wheels, then all the wheels would turn on the rails, and shafts 57 and 58 would turn 60 in opposite directions, no motion would pass through the differential box and the train of gears driven by gear wheel 61 would stand still.

Now gear 61 may be connected through

the king pin of the master truck as shown 65 in Figs. 10 and 11, so as to drive another differential gear mounting as shown at 64 in which the gear 65 would be driven by the train of gears and shafts, as shown, by gear 61, while gear 64 would be driven from the 70 other end by means of another system of shafts and gears either by a hand crank 66 or by an electric motor 67. This arrangement of gears would enable either the train 75 of gears driven by 61 or the train of gears 80 driven by the hand crank and motor to drive the central frame of the differential device at 64 at half speed of either of the moving trains. In the arrangement shown this central spindle is keyed to a shaft which passes 85 through the hollow quills in the trains of gears from 61 or from the hand crank to the pair of bevel wheels 68, one of which is mounted as shown on a crank axis 69 carrying crank disks 70 at each end connected in 90 turn by suitable connecting rods 71 to the gun so that when the disk of the differential case 64 is revolved either by hand (or motor) from one end or by the motion of gear 61 from the other end, the elevation of the gun 95 will be affected and regulated by means of the crank axle and the connecting rods.

The operation of this device would be, then, that if the hand (or motor) elevating or depressing device were standing and the 95 train of gears 61 were actuated by the recoil of the gun, as explained above, the consequent revolution of the crank disks 70 would pull the gun down to a level position in which it could be readily loaded.

100 It will be understood that the ratios of the gearing will be so figured that there will be sufficient scope of action to pull the gun to a horizontal position from its maximum elevation. If the gun should be fired from 105 some elevation less than the maximum the effect of the recoil would be to pull the gun down to the horizontal position for loading beyond which it could not go because of stops, and after reaching that position the 110 train of gears acting through 61 would be pulled to a standstill and the free truck wheels in truck 27 would thereafter be compelled to slide on the rails until the remaining energy of the recoil of the gun was 115 spent.

The gun could be elevated or depressed 120 by means of the hand crank or electric motor acting through the other end of the differential case 64 quite independently of the movement of the bevel wheels controlled by the movement of the carriage as a whole through gear 61. The operation of the hand or electric elevating mechanism offers nothing new and need not be further touched 125 upon.

It will be understood that the carriage as a whole will be equipped with ordinary car

couplers 72 at each end for movement to some distance by a locomotive and that one of the trucks would be provided with suitable slow means for slight movements along 5 the tracks either by hand or by electric or other power. These features are of well known construction and need not be illustrated or described in detail.

Various modifications and developments 10 of the illustrated construction shown will readily occur to those skilled in the art, without departing from what I claim as my invention.

I claim as my invention:—

15 1. In coast defense ordnance and the like, a traveling support, a gun mounted thereon in fixed position with relation to azimuth pointing, and a track curved on the arc of a true circle approximately tangent to the

20 longitudinal axis of the gun and having a known angle and distance relation to the base line of the range-finding survey system, on which track the support is traveled for azimuth pointing of the gun.

25 2. In coast defense ordnance and the like, a traveling support, a gun mounted thereon in fixed position with relation to azimuth pointing, and a track curved on the arc of a true circle approximately tangent to the

30 to the longitudinal axis of the gun and having a known angle and distance relation to the base line of the range-finding survey system, on which track the support is traveled for azimuth pointing of the gun, and 35 means for forcing the gun support to travel in the arc of a true circle on said track when the gun is pointed.

3. In coast defense ordnance and the like, a traveling support, a gun mounted thereon in fixed position with relation to azimuth 40 pointing, but susceptible of angular elevation, and a track curved on the arc of a true circle approximately tangent to the longitudinal axis of the gun and having a known

45 angle and distance relation to the base line of the range-finding survey system, on which track the support is traveled for azimuth pointing of the gun.

4. In coast defense ordnance and the like, 50 a traveling support, a gun mounted thereon in fixed position with relation to azimuth pointing, and a track laid on the arc of a true circle tangent to a line near, and parallel to the axis of the gun and having a

55 known angle and distance relation to the base line of the range-finding survey system, on which track the support is traveled for azimuth pointing of the gun.

5. In coast defense ordnance and the like, 60 a traveling support, a gun mounted thereon in fixed position with relation to azimuth pointing, and a track laid exactly level and of accurate gage curved on the arc of a true circle tangent to a line near, and parallel to,

the axis of the gun and having a known 65 angle and distance relation to the base line of the range-finding survey system, on which track the support is traveled for azimuth pointing of the gun.

6. In coast defense ordnance and the like, 70 a traveling support, a gun mounted thereon in fixed position with relation to azimuth pointing, and a track laid exactly level on the arc of a true circle on which said support is traveled for azimuth pointing of the gun, 75 the latter lying in such a position that its axis is constantly tangent to an imaginary cylindrical surface generated around the center of the circular track, which center together with the radius joining it with the 80 axis of the gun is in known angle and distance relation to the base line of the range-finding survey system.

7. In coast defense ordnance and the like, 85 a traveling support, a gun mounted thereon susceptible of angular elevation, and a track curved on the arc of a true circle approximately tangent to the longitudinal axis of the gun, and having a known angle and distance relation to the base line of the 90 range-finding survey system, on which track the support is traveled for azimuth pointing of the gun.

8. In coast defense ordnance and the like, 95 a traveling support, a gun mounted thereon susceptible of angular elevation, and a level track on the arc of a true circle on which said support is traveled for azimuth pointing of the gun, the latter lying in such 100 a position that its axis is constantly tangent to an imaginary cylindrical surface generated around the center of the circular track, which center together with the radius joining it with the axis of the gun is in known angle and distance relation to the base line 105 of the range-finding survey system.

9. In coast defense ordnance and the like, 110 a traveling support, a gun mounted thereon, tracks on which said support travels, and friction shoes sliding on said tracks 115 together with means carried by the support for moving the shoes, said means being sufficient to overcome the sliding friction of the shoes on the track, but insufficient to overcome any considerable inertia of the shoes developed by a sudden movement of the gun support.

10. In coast defense ordnance and the like, 120 a traveling support, a gun mounted thereon susceptible of angular elevation, and a track on which said support travels and gearing operated by the wheels of the support on recoil after firing for lowering the gun to position for reloading.

11. In coast defense ordnance and the like, 125 a wheeled support, a gun mounted thereon and susceptible of angular elevation, means for blocking certain of the support wheels

against rotation on recoil after firing and gearing operated by the unblocked wheels during the recoil movement for lowering the gun to position for reloading.

5 12. In coast defense ordnance and the like, a wheeled support, a gun mounted thereon and susceptible of angular elevation, means for blocking certain of the support wheels

against rotation on recoil after firing and differential gearing operatively connected 10 to the block and unblocked wheels and serving during the recoil movement to lower the gun to position for reloading.

In testimony whereof I have signed my name to this specification.

AUGUSTUS SMITH.
